UNITED STATES PATENT OFFICE.

LUTHER W. HARWOOD, OF TROY, NEW YORK.

IMPROVEMENT IN GRATES FOR STOVES.

Specification forming part of Letters Patent No. 39,811, dated September 8, 1863.

To all whom it may concern:

Be it known that I, LUTHER W. HARWOOD, of the city of Troy, in the county of Rensselaer and State of New York, have invented certain new and useful Improvements in Grates for Stoves, Furnaces, &c., of which the following embraces a sufficient description, reference being had to the annexed drawings, in which—

Figure I is a top view, and Fig. II a bottom view, of a stove-grate embodying my said invention. Figs. III and IV are bottom views of parts of that grate, and Fig. V is a perspective view showing the upper side of the same grate inclined as when dumping burned coal from the grate. Fig. VI is a bottom view of the outer frame of the grate, shown in Figs. I and II. Fig. VII is a bottom view of the whole, and Fig. VIII, a bottom view of a part, of another stove-grate embracing my said invention. Fig. IX is a side view, and Fig. X is a longitudinal section, of parts of the grate shown in Figs. I, II, V, and VII; and Fig. XI is a perspective view of the under side of the grate shown in Figs. I, II, and V. Fig. XII is a view of a handle for use in operating the grates shown by Figs. I, II, V, VII, and XI; and Figs. XIII and XIV are cross-sections of the grate shown bottom side up in Fig. II.

The same letters refer to like parts in all the figures, and the arrows therein indicate the directions in which the parts are moved.

Some stove-grates have heretofore consisted of two longitudinal parts or sub-grates placed side by side, and so that each sub-grate could be reciprocated endwise along the other one to agitate burning coal on the grate and sift ashes therefrom; but I am not aware that such sub-grates could also be rocked or turned together as one grate on an axis common to both sub-grates from a horizontal into a vertical or inclined position to dump refuse coal and ashes from the grate.

Now, a part of my invention consists in making a grate for stoves, furnaces, &c., with two sub-grates, B C, arranged together side by side, and supported at their ends by compound journals D D', composed of two shanks, b b', Fig. X, fast on one sub-grate, B, and two other shanks, c c', Fig. IV, fast on the other sub-grate, c, all fitted together in pairs within suitable sockets or bearings, d d', so that each

of the sub-grates B C can be slid to and fro on its own shanks, b b' or c c', and along the other sub-grate to agitate burning coal on the grate and sift out ashes therefrom, and so that the said sub-grates B and C can also be rocked or turned together as one grate on the said combined shanks as an axis common to both sub-grates from a horizontal into a vertical or inclined position, and vice versa, to dump refuse coal and ashes from the grate and return the grate into the proper horizontal position for having a fire made thereon. As regards this part of my invention, I generally prefer to have the shanks b b' and c c' in the form of half-cylinders, as in Fig. XIII, and arranged with their flat sides against each other and in a plane perpendicular or nearly so to that of the grate, and with both of the shanks of each journal resting directly against, and held together by, their respective supporting sockets or bearings d d'; but I do not limit myself to that particular way of shaping, arranging, and holding together the shanks which constitute the divided or compound journals that are common to the two sub-grates, and whenever desirable I adopt any other suitable construction thereof which will allow the sub-grates to be slid to and fro along each other on their respective shanks, and also rocked or turned together like one grate on the said combined shanks as an axis common to both of the sub-grates; and I also generally prefer to rock or tilt the grate by applying power to one of its divided journals, D, Fig. I, where it extends outside of its supporting socket d, by means of a suitable removable handle, E, Fig. XII, and to reciprocate the sub-grates B and C simultaneously in opposite directions or along each other when in the proper horizontal position by applying power to the ends of the sub-grates substantially in the manner hereinafter particularly specified; but I do not limit myself to those modes of operating the sub-grates, and shall rock and reciprocate them by applying power through any suitable devices to either the shanks, ends, or sides of the sub-grates as shall be deemed preferable; and, so far as regards the above specified part of my invention, I adopt any suitable means to counteract the natural tendency which the sub-grates have when in a horizontal posi-

tion and loaded with coal to lop or turn down on their shanks, and by their leverage press or bind their said shanks hard against each other, or against the inner side of their supporting-sockets, and thereby make frictional resistance to the reciprocating or rocking movement of the sub-grates; but I generally prefer to accomplish that object by means of a device attached to or forming a part of and moving with the sub-grates, and without obstructing the upper surface of the grate or materially encumbering the lower side thereof. To that end I make one or both of the sub-grates B C, with an arm or arms, G, Figs. II, IV, VII, XI, and XIV, fast to one sub-grate, B or C, and extended laterally along and fitted to or against the under side of the other sub-grate, C or B, so as to thereby make the sub-grates mutually support each other in their proper relative positions, whether the grate is in motion or stationary in any required posture, and so as to likewise prevent the sub-grates, when horizontal and loaded with coal, from lopping or turning down under the weight thereof, so as to thereby make the shanks $b b' c c'$ of the sub-grates bind together in or against their supporting-sockets $d d'$. This arrangement of an arm or arms, G, with two sub-grates, B C, mounted on shanks $b b' c c'$, which together form two divided journals, D D', common to the two sub-grates, as above described, constitutes another part of my invention.

Another part of my invention consists of the arrangement, in combination with two sub-grates B C, mounted so as to be capable of sliding endwise past each other and of turning together sidewise in a frame, A, substantially as hereinbefore described, of a pair of vibrating levers, H H, two pairs of followers, f f f f, and two connecting-rods, K K, so that when the said sub-grates B C are reciprocated endwise in a horizontal position with coal on them the said followers f f f f will then recede before and follow after the ends of the sub-grates, and thereby prevent the coal from falling down into and clogging up the spaces which are between the ends e of the frame a and the ends g of the sub-grates, and which are alternately enlarged and contracted by the reciprocating movements of the sub-grates; and so that the two sub-grates B C will be simultaneously, and yet independently, reciprocated side by side in opposite directions when in the horizontal position by vibrating one of the levers, H, by means of a handle, E, Fig. XII, applied to a corresponding part, J, Figs. II, III, VII, VIII, and XI on the lever, while the sub-grates B C are constantly free to be rocked or turned sidewise as one grate on a common axis. In the practice of this part of my invention I have the levers H H pivoted at or about the middle, to the fixed frame A, or its equivalent, and I generally prefer to either have the followers or drivers f f f f fast upon or form part of the levers H H, as shown

in Figs. II, III, and XI, with the latter united to the connecting-rods K K by pivots h in their ends, or to have the followers f f f f fast upon or form part of the connecting-rods K K, as shown in Figs. VII and VIII and united loosely by studs i i, or their equivalent, to the levers H H, so as to be thereby reciprocated endwise on the frame A when the said levers are vibrated.

In order to more readily keep the grate in the proper horizontal position while burning coal thereon, I generally prefer to have one side, B, of the grate a little wider than the other side, C, and supported by a stop, F, Figs. II, VI, VII, and XI, so that the grate can be tilted sidewise in only one direction to dump refuse matters off from the grate; and when the grate is thus tilted, as shown in Fig. V, the sub-grates B C and the followers f f f f are then liable to become slid or moved out of their proper places in respect to each other, so that the sub-grates may hit against and be stopped by the followers on attempting to turn the grate back into the horizontal position. To overcome that difficulty without encumbering the upper side of the grate, I arrange an inclined projection or guide, m, Figs. II, VII, X, and XI, fast on the under side of each end of that half-grate B which is elevated when the grate is tilted, and also arrange a similar guide, n, Figs. II, III, V, VII, VIII, XI, and XIII, on the under side and at the inner ends of those followers, f f, which are opposite to that part, C, of the grate which is depressed when the grate is inclined, so that while the grate is being turned back from the vertical or inclined position to the horizontal one the inclined guides m and n on the sub-grate and followers will then guide and force the followers and sub-grates back into their proper relative positions. When the half-grates B C are free to be tilted sidewise in either direction, I then arrange the inclined guides m and n in the same manner on the under sides of both of the sub-grates B C and on all four of the followers or drivers f f f f.

What I claim as new, and of my invention, and desire to secure by Letters Patent, is—

1. Two sub-grates, B C, mounted side by side on shanks which are fast on the sub-grates, and so shaped and arranged together in sockets or bearings that the said sub-grates can be reciprocated along each other on their respective shanks, and also rocked or tilted together like one grate on the said combined shanks as an axis common to both sub-grates, substantially as herein set forth.

2. In combination with two reciprocating and rocking sub-grates mounted together on divided journals common to both sub-grates, substantially as herein described, a supporting arm or arms, G, arranged on the under side of and carried by the said combined sub-grates, substantially as herein set forth.

3. The combination of a pair of levers, H

H, two sets of followers or drivers, *ffff*, and two connecting rods, K K, with two sliding and turning sub-grates, B C, mounted together on divided journals common to both of the said sub-grates, substantially as herein set forth.

4. In combination with two sliding and turning sub-grates, B C, mounted together on divided journals common to both sub-grates, and provided with drivers or followers *ffff*,

substantially as herein described, the inclined guides *m n*, arranged on the under side of and carried by the said combined sub-grates and followers, substantially as herein set forth.

LUTHER W. HARWOOD.
